Schenectady, N. Y., assignors to Consolidated
Car Heating Company, Inc., Albany, N. Y., a
corporation of New York

Application January 20, 1934, Serial No. 707,436

15 Claims. (Cl. 40—53)

This invention relates to remote controlled devices, such as signs, particularly signs for use in connection with railways, and more especially signs for use in connection with a plurality of cars, units, or compartments connected to form a train.

On railways, railway employees' time is saved and travelers' journeys are facilitated by a profuse use of informative signs. This is particularly true in the case of high speed urban lines, where the destinations and routes are so numerous, particularly in the case of those in large cities, such as New York, especially where those lines or railways are underground, where a passenger does not have an opportunity to ascertain the general direction of movement of trains by comparison with known wayside points. On such lines, it is quite desirable to have informative signs, readable both from without and within the train, associated with each car, unit, section, or compartment, and preferably positioned at each end and at the center thereof.

On the rapid transit lines of New York, at certain hours, the number of passengers is so great that even if an employee were stationed on each car, unit, section, or compartment of a train, it would be difficult for that employee to make his way from one end of the unit to the other and back again, through the mass of passengers, to properly change the signs, so that the persons awaiting trains at the various stations and on the train will be informed of the desired facts in regard to route, destination, and so forth regarding the train.

Trains composed of a very large number of cars, units, or compartments are now being operated by two and sometimes by one man, such as the so-called motorman and the so-called rear flagman. To change all of the signs on all of the cars when only one or two employees are used on a train composed of say, eight, twelve, or sixteen cars is a task which could only be successfully accomplished in a short time while the train is at a terminus and while free from passengers.

A principal object of this invention is to provide signs of such construction that the requisite number may be well placed in each car, unit, section, or compartment of a multiple unit train, and a convenient and easily operated means may be installed at one or more points in the train; whereby all signs of a given kind distributed throughout the train, such as, for instance, route signs, may be simultaneously operated; and whereby other signs, all of the same kind, dis-

tributed throughout the train, such as, for instance, destination signs, may be simultaneously operated; and whereby further signs, distributed throughout the train, giving further desired information, all of the same kind, may be simultaneously operated.

A further object of this invention is to provide setting means at one or more points on a train whereby a plurality of signs, of different informational type on the train may be operated, in a case where the signs are arranged in sub-groups of one or more, remotely positioned one to the other, each sub-group having an operating motor associated therewith, and the signs arranged in one or more main groups, each main group consisting of all sub-groups of the same informational type.

A further object of the invention is the provision in a system of the type pointed out of indicating means whereby the proper setting of the several signs will be indicated to the one setting the signs.

A further object of the invention is the provision, in a system of signs, consisting of main groups, each main group consisting of sub-groups, and each sub-group consisting of one or more signs, of selector mechanism common to all the main groups but sign operating motor control individual to each main group.

A further object of the invention is the provision of a plurality of signs, disposed in a plurality of positions, as throughout a train in the several cars, operable by a minimum of manipulations by one person at one point.

A further object of the invention is the provision of signs of the type specified which may be controlled manually, but operated by power.

A further object of the invention is a provision of signs of the type specified which may be moved synchronously from one position exhibiting one indicia, to another position or positions indicating another or other indicia.

A further object of the invention is the provision of signs of the type specified which are arranged so that if any particular sign having a plurality of indicia thereon, gets out of step or synchronism, it automatically gets back into step in the normal operation thereof without requiring particular and special attention by the person operating the signs.

A further object of the invention is the provision of a system whereby a sign is moved to its several informational positions by power means having associated therewith means for automatically controlling the power means so that the

several positions of the sign will be definite and precise.

A further object of the invention is the provision of a system of signs of the type specified which will be so arranged that any number of units equipped therewith may be connected together to form a train and any number of trains may be connected together to make a larger train, and the system will continue to function in an identical manner.

A further object of the invention is a system of the type specified in which only one main conductor throughout the train is required for each distinct informational indicia on the sign having the largest number of informational indicia thereon; one motor control wire for each main group of signs; and one indication wire for each main group of signs.

Other objects and advantages will appear as the description of the particular physical embodiments selected to illustrate the invention progresses, and the novel features will be particularly pointed out in the appended claims.

In describing the invention in detail and the particular physical embodiment selected to illustrate the invention, reference will be had to the accompanying drawings, and the several views thereon, in which like characters of reference designate like parts throughout the several views, and in which:

Figure 1 is a schematic or diagrammatic view of a train composed of a plurality of units, each unit being either what is known commonly as a car, or compartment, or as a section of the newer type of what is known as an articulated train, with signs of applicants' construction indicated in place therein; Fig. 2 is a somewhat schematic view illustrating, in plan, one preferred arrangement of operating motor, signs associated therewith, and operating connections therebetween; Fig. 3 is a somewhat schematic elevational view of the device as shown by Fig. 2; Fig. 4 is a plan view of a sign operating motor, driving connections and circuit controllers, with part of the inclosing cover removed to more clearly show the internal construction; Fig. 5 is a sectional view on the plane indicated by the line V—V of Fig. 4 viewed in the direction of the arrows at the ends of the line; Figs. 6, 7, 8, 9, and 10 are schematic or diagrammatic illustrations of the selecting, controlling, operating, and indicating circuits and the devices associated therewith positioned on the several units of a multiple unit train and are to be read in connection one with the other, as Fig. 7 is a continuation of the right hand end of Fig. 6, Fig. 8 of the right hand end of Fig. 7, Fig. 9 of the right hand end of Fig. 8, and Fig. 10 of the right hand end of Fig. 9; Fig. 11 is a schematic view of an alternative form of construction for a selective circuit controller; Fig. 12 is an elevational view of a hand plug to be used with the alternative scheme as shown by Fig. 11; Fig. 13 is a fragmentary sketch illustrating an additional means of control for the motor operating a sign; Fig. 14 is a schematic showing of an alternative form of motor circuit.

In order to better explain the principle, the construction and the mode of operation of the invention, applicants have shown the application thereof to a specific arrangement of signs on a train.

In Figure 1, applicants have illustrated a number of passenger receiving units. Each one of these units may be considered as an ordinary car

or as one of the sections of an articulated train. The units are designated A, B, C, B', and A'.

When such a train, as is illustrated by Fig. 1, starts from a terminus or comes into a station to receive passengers, it is desirable, for the train to exhibit along at least one side thereof, one or more signs having indicia thereon indicative of the destination of the train, and/or the general route to be taken by the train, and/or in some cases, the fact that the train is going to pass over a general route by someone of several alternative lines. In short, prospective passengers in a terminus or station should be able to determine the facts in regard to the train which are necessary to be known to enable a prospective passenger to determine whether or not he should board the train. This requires that a sign or signs be so exhibited that they may be read by persons standing on a passenger loading platform as a train passes alongside of that platform and comes to a stop. Preferably, several signs, all bearing the same indicia should be exhibited along the length of the train.

It is also preferable after one has actually boarded the train, that he may check the destination of the train, or some other information concerning the route or routes to be traversed by the train.

In order to provide the necessary signs for supplying the desired information, applicants contemplate arranging signs, sufficient to give the necessary desired information, so that they may be viewed by passengers on a loading platform. To this end, applicants arrange signs, as in section A, at 1, 2, and 3. These signs are arranged, as will be hereinafter more fully explained, so as to be readable from the right hand side of the train, as shown in Fig. 1, when traveling in the direction of the arrow 4. Applicants may also arrange corresponding signs, as 5, 6, and 7, readable from the right hand side of the train as shown in Fig. 1, when the train is traveling in a direction opposite to that of the arrow 4.

Applicant may arrange signs upon each of the sections B, C, B' and A' exactly corresponding to the signs 1, 2, and 3, and 5, 6, and 7 on section A or may diminish the number of signs, that is, as shown on sections B and B', signs, as 8 and 8' only, may be exhibited on one side of the train, and signs, as 9 and 9' only, on the other side of the train.

If desired, no signs, or one, two, or more signs may be exhibited in each unit of the train on one side thereof, or no signs, or one, two, or more signs may be exhibited on the other side of each unit of the train.

Section C has been provided by applicants with three signs on each side thereof, that is, signs 10, 11, and 12; and 13, 14, and 15. Section A' has been provided by applicants with three signs on each side thereof and indicated at 16, 17, and 18; and 19, 20, and 21.

In addition to the signs readable from the loading platform by which the train passes, applicants also provide signs which are readable from within each unit of the train. In each of the sections, applicants have provided central signs, as 22, 23, 24, 25, and 26. These signs are to be positioned so as to be readable by passengers within the unit. In addition, applicants provide signs at the ends of some of the sections, as 27, and 28, at the several ends of section A; 29 and 30, at the several ends of section C; and 31 and 32, at the several ends of section A'.

It is applicants' intention to arrange their sys-

tem so that all of those signs which are positioned substantially adjacent to one end of a unit are all operated by one motor; and those substantially adjacent the center of a unit to be likewise operated by a separate single motor, thus signs, 1, 5, and 27 will be operated by one motor; signs 2, 6, and 22 will be operated by another motor; and signs 3, 7, and 28 will be operated by still a third motor. Each of the groups, as 1, 5 and 27, 10 is designated a sub-group by applicants.

Where one sub-group of signs is used in a unit, as signs, 2, 6, and 22, they will in general be signs which indicate the destination of the train; where two sub-groups of signs are used in a unit, as signs 2, 6, and 22 and 1, 5, and 27, one would be a destination sub-group and the other would be a general route sub-group; if three sub-groups of signs are used in one unit then the additional sub-group as 3, 7, and 28 would be signs indicating a general route and a specified alternative of that route. It is, of course, to be understood, that if desired, the destination sub-group of a particular unit, as sub-group 2, 6, and 22 of unit A may be absent, but the other two sub-groups as 1, 5, and 27, and 3, 7, and 28 may be present. In fact, the number of signs and the positions of the signs in any given unit may be as desired. There may be a total absence of signs; or one or any plurality of like sub-groups; or any plurality of unlike sub-groups, each sub-group containing one or any plurality of signs.

Applicant's system of signs, as exemplified by the arrangement of Fig. 1 results in the presence of numerous sub-groups, each consisting of one or more like signs. These sub-groups fall into main groups, each main group including all sub-groups throughout the train bearing like indicia. There are three main groups shown in Fig. 1; the one containing all the destination sub-groups, that is, the sub-groups including signs 22, 23, 24, 25, and 26; the one containing all the route sub-groups, that is the sub-groups including signs 27, 28, and 31; and the one containing all the specified alternatives of a general route sub-group, that is, the sub-group including signs 28, 30, and 32.

It is, of course, to be understood that the illustration and description of only three main groups is not to be understood as excluding the use of more main groups, because as will be apparent from the hereinafter given description, applicants' invention is applicable to any plurality of main groups.

Each sign of applicants' invention bears one or a plurality of informational indicia thereon, and includes means whereby a particular distinct indicia may be conditioned so as to be exhibited to passengers. Various methods may be employed to cause the exhibition of this indicia. Applicants have illustrated and described one method which involves a plurality of faces each movable to a predetermined position, but it is to be understood that applicants do not intend to thereby exclude a single movable face, or a single stationary face cooperating with a movable shield, from the domain of their invention.

Each sign of applicants' preferred construction is in general a hollow body and preferably provided with a plurality of plane faces. The form illustrated in the drawings for the purpose of explanation of applicants' invention is that of a hollow cylindrical prism having six plane faces 33, 34, 35, 36, 37, and 38. By so constructing the indicia bearing portion of the sign, ap-

plicants are enabled to cause each sign to exhibit a multiplicity of different information indicia. In the form shown, each sign may exhibit six distinct informational indicia.

Each sign is supported on a longitudinal axis 5 39 suitably supported in bearings, as 48 and 41, so that those signs which are mounted adjacent the sides of the units may be revolved about their axes to bring each of the plane faces, as 33 to 38, inclusive, in position to be visible 10 along the side 42 of the train and preferably through a transparent window, and those signs which are mounted on the center line of a unit, as sign 22 of section A, are positioned so that the plane faces thereof, as 44, may be exhibited 15 to full view of passengers facing it in the unit.

Each of the side signs is mounted on a longitudinal shaft 39 and have a beveled gear 45 attached to one end thereof. This beveled gear meshes with a companion beveled gear 46 mounted on a shaft 47 which is supported in suitable bearings, as 48 and 49. The other end of shaft 47 bears a beveled gear 50 meshing with a beveled gear 51 on the end of a shaft 52, one end of which is supported in bearing 53, and the other end of which is connected by universal coupling 54 with a shaft 55 driven by the motor M.

Shaft 55 also, on its other end, has universal coupling 56 connecting with shaft 57 which is 30 in turn connected to universal coupling 58 which is mounted on shaft 59 carrying the sign having the plane face 44. The shaft 59 is mounted in bearings, as 60 and 61, and the other end thereof has a universal coupling 62 attached thereto which, through the shaft 63 corresponding to shaft 52, operates the sign on the other side of the car.

By the arrangement hereinbefore described, the sign in the center of the car together with the signs on each side of the car is operated 40 synchronously by one and the same motor by means of connections which insure all of the signs operated from a single motor being in step after once being connected up in step.

Of course, it is understood that although applicants have provided that motor M may be used to operate three separate and individual signs at one and the same time, it may, as is evident, operate only one sign or two signs, and it is to be further understood that applicants do not mean to exclude a construction in which a single motor operates any number of signs, as it is evident that just as two signs, as the sign in the center of Fig. 3 and the one to the right thereof, are operated in tandem from motor M, so may any number of signs be operated in tandem from coupling 56 through motor M. It is further to be understood that applicant does not intend to exclude signs operated in other than tandem by well known mechanical movements operated by motor M, just so long as those signs are so connected as to operate synchronously.

The operating motor M, and its connections to the universal joint couplings 54 and 56, are best shown in Figs. 4 and 5. The motor M may be of any of the usual forms of motors as series, shunt, or compound wound, and operable by alternating or direct current. It is to be understood, of course, that applicants, by the showing of an electric motor acting as a prime mover, do not mean to exclude the use of equivalent prime movers.

Motor M, as is usual, is provided with a shaft 64. This shaft bears a pinion 65 which meshes 75.

- with a gear wheel 66 mounted to turn with shaft 67 supported in suitable bearings. The shaft 67 bears a pinion 68 attached to rotate therewith which meshes with gear wheel 69 mounted to turn with shaft 70 mounted in suitable bearings. The shaft 70 has mounted thereon so as to be movable therewith a drive pin 71 which upon rotation engages in slots as 72 of the star wheel 73 mounted rigidly on shaft 74. The star wheel 73 is provided with slots to correspond with the number of plane faces on the plural faced sign, that is, with six slots, as 72. When driving pin 71, during rotation, engages with a slot as 72 it moves the star wheel 73 and shaft 74 through an angle of 60 degrees and locking cam 75 engages, at times, with the arcuate locking surface, as 76, between slots of star wheel 73 so that star wheel 73 is prevented from turning, that is, is locked.
- 20 The shaft 74 is supported in suitable bearings and is otherwise properly arranged in accordance with good engineering practice and has connected thereto the universal joint 54 at one end and the universal joint 56 at the other end through which connection is made to signs to be operated.
- 25 The shaft 70 carries a drum 77 preferably formed of insulating material and provided in the usual way with a metallic contact strip 78 for cooperation with the contacting fingers 79 and 80 for a purpose to be hereinafter more fully described.
- 30 The shaft 74 carries a drum 81, termed, by applicants, a motor operated selective circuit controller, preferably of insulating material, having contacting fingers 82, 83, 84, 85, 86, 87, 88, 89, and 90 arranged to bear upon the periphery thereof or upon metallic strips imbedded in the periphery, but not shown in Fig. 4 although shown clearly and diagrammatically in Figs. 6 to 10 inclusive.
- 35 From the hereinbefore given description, it is apparent that if electrical energy is supplied to the motor M the drum 77 will be rotated together with shaft 74 and drum 81 so that the sign or signs connected to universal couplings 54 and 56 will be rotated. In describing Figs. 6 to 10 inclusive it will be pointed out how the driving pin 71 is caused to rotate star wheel 73 through only 60 degrees or any multiple of 60 degrees as desired so as to bring any desired face of a sign to a given position.
- 40 It is, of course, to be understood that although applicants have herein shown a sign having six faces and a star wheel 73 having six slots 72 therein so that upon an operation of the motor M the star wheel 73 is moved through an angle of sixty degrees and some one of six faces of a sign is exhibited, it is to be understood that forms other than hexagonal prisms may be used.
- 45 for signs and in such case the star wheel 73 will be moved through a number of degrees corresponding with the number of faces. The star wheel 73 will be provided with a number of slots 72 also corresponding with the number of faces on the sign because applicants may use, in accordance with the principles of the invention less than six faces or more than six faces.
- 50 Various arrangement of circuits and controlling relays, together with manually operable circuit closing devices may be employed to operate and control the signs positioned upon the several units of a train, but in order to obtain and make
- 55 use of the full capabilities of applicants' signs,

applicants have devised a system of control whereby the signs throughout the train may be controlled from one point, or from two or more points, preferably two, one located at one end of the train, and one located at the other end of the train.

The system of control devised by applicants is illustrated in Figs. 6 to 10 inclusive. These figures when placed end to end; so that the left hand end of Fig. 7 joins the right hand end of Fig. 6; the left hand end of Fig. 8 joins the right hand end of Fig. 7; the left hand end of Fig. 9 joins the right hand end of Fig. 8; and the left hand end of Fig. 10 joins the right hand end of Fig. 9, exhibit all of the necessary circuits for a five unit train, so that Fig. 6 exhibits the necessary mechanism and circuits on the section A of Fig. 1; Fig. 7 illustrates the necessary circuits and mechanism on section B; Fig. 8 illustrates that on section C; and Fig. 9 that on section B'; and Fig. 10 illustrates that on section A'. Sections A and A' are, in effect, identical, one being one end of the system, and the other being the other end. The arrangement for section B is the same as the arrangement for section B'. The arrangement of C is identical with that of A and A' except the means provided for operating the signs is absent.

As the units of the train may be either articulated or coupled, it may be necessary to provide conductor couplings between the several sections. These couplings between A and B are indicated at 91 and 92; between B and C at 93 and 94; between C and B' at 95 and 96; and between B' and A' at 97 and 98. In case a train, such as is shown in Fig. 1, is coupled to another corresponding train so as to be operated as one, then if it is connected to A, coupling 99, Fig. 6, is attached thereto; if it is attached to section A', then coupling 100 is attached thereto.

It is, of course, to be understood that the arrangement of sections or units A and A' may be varied, in that the particular kind of signs may be as desired, that is, all signs may be absent from sections A or A' or one, two, or more different types of signs belonging to different main groups may be present.

It is also to be understood that sections B and B' although shown as having the mechanism for operating one type only of sign may be equipped to operate one, two, or more types of signs, or may have no signs at all therein although conductors and wires would pass through the unit.

In each of sections A and A', devices are positioned which may be manually operated to position any one or more of the several types of signs positioned throughout the train and for indicating that the signs have assumed the desired position.

In order to operate any and all of the signs shown, throughout the train, or throughout a double, or triple train, applicants require twelve wires extending throughout the train. These wires are the conductors which are coupled together by the coupling members such as 91 and 92.

If one has to operate the form of applicants' invention, as illustrated by this application, as applied to a five section train with the various parts arranged as shown by Figures 6 to 10 inclusive, a trainman, stationed in section A, that is, in the section arranged as shown by Fig. 6, would first place a circuit controller to the on position, that is, would operate circuit controller ED. He would then position partial circuit selec-

5 tive circuit controller D of Fig. 6 to a position corresponding to a particular distinct indicia desired. The trainman would then operate a manually operable circuit controller individual to the particular main group of signs to be operated. Such a circuit controller is indicated at 233. The trainman would then wait for an indication which he would receive by the lighting of a lamp individual to the main group of signs which he desires to have operated. Such a lamp is shown at 259. The only further action necessary by him would be to place the circuit controller ED in the off position. If the trainman were in section A', the mode of operation would be the same, as duplicates of all of the devices mentioned are located in section A'.

10 The circuit controller ED is in function merely a manually operable circuit controller which in one position, which may be called the off position, normally closes one circuit, and when in another position, which may be called the on position, breaks the first mentioned circuit and closes other circuits and is primarily for connecting the several circuits with the positive terminal 15 of a source of potential. It is, of course, obvious that other forms of circuit controller than the particular one illustrated by applicants may be used.

15 The partial circuit selective circuit controller 30 is in function merely a means for partially closing at will, any one of a plurality of partial circuits, and in its simplest mechanical form may be pictured as a swinging arm which sweeps over a plurality of contacts each of which is connected 35 to a conductor where the arm is connected to one terminal of a source of potential and the several conductors are each included in separate circuits.

20 The manually operable circuit controller, such as 233 functions exactly like, and in construction 40 is comparable to any ordinary circuit controller which when operated by hand closes a circuit.

25 The partial circuit selective circuit controller 45 in the form shown by applicants embodies a drum corresponding to the drum 81 of Fig. 4 in that it is rotatably mounted and has metallic segments 50 in the periphery thereby cooperating with contact fingers arranged in relation thereto in a manner corresponding to the relation of contact 55 fingers 82 to 99 inclusive of Fig. 4 in relation to drum 81. The manually operable drum and associated contact fingers is indicated in Fig. 6 as a 60 whole by the letter D. It is rotatable in a direction corresponding to the arrow 191 and has six working positions as indicated by lines 102, 103, 104, 105, 106, and 107. When in position 102, contact fingers 111 and 112 both bear upon the metallic segment 115. When the drum is moved to position 103, contact finger 111 still bears upon segment 115, but contact finger 112 moves out 65 of contact with 111, and contact finger 113 contacts with segment 116 which is connected by conductor 117 with segment 111. In the same way, further movement of the drum D causes 70 118 to contact with 114; and 119, 120, and 121 to contact with 119, 109 and 108 respectively.

75 If it is desired to position a route sign throughout the train to a position so that some one of its six faces will be exhibited, energy drum ED is operated so that metallic segments 122, 123 and 124 are moved so that 122 bridges contact fingers 125, 126 and 127; segment 123 bridges contact fingers 129 and 130 and 124 is moved out of contact with 130 and 131, then the drum D is placed in that one of its positions, 102 to 107 inclusive, 75 which corresponds with desired face to be ex-

hibited. When drum D has been moved as described, then route button 132 is depressed to make contact between wires 133 and 134. Under such conditions, when drum D is in number one position, that is, in position 102, as shown in Fig. 6, current flows from the positive terminal of the battery through wires 135 and 136 to contact finger 127, through contact segment 122 to contact finger 126, wire 137 and wire 133 to contact button 132, thence to wire 134 and through wires 138 and 139 to armature 140 and then through wire 141 to relay, or motor control, or electrically energizable coil 142 and thence to the negative terminal of the source of potential. Current flowing in the above traced path energizes 15 relay coil 142 and causes its armatures 143 and 144 to be moved to the left, as shown in Fig. 6, making contact with wires 145 and 146 which are both connected to wire 147 leading to the positive terminal of the source of potential. 20 When these armatures 143 and 144 are thus moved, current flows through wire 147 and wire 145 through armature 143 and wires 148 and 139 through armature 140 to wire 141 and relay coil 142 to the negative terminal of the source. This 25 last traced circuit is in the nature of a stick circuit to maintain the energization of relay coil 142 even if the finger is removed from button 132.

30 Not only does current flow in the last above traced path but also current flows from the positive terminal of the source through wires 147 and 143 through armature 144 to wire 149 through motor 150 and to the negative terminal of the source. The motor 150 is one of the motors 35 M as shown in Fig. 4 and is connected to operate the motor operated selector circuit controller or route drum RD corresponding to drum 81 of Fig. 4. As route drum RD turns, its several contact segments pass in succession into contact with the contact fingers arranged about the periphery 40 thereof. These contact fingers have positions corresponding to the positions of the contact segments of manually operated drum D, that is, they have positions 152, 153, 154, 155, 156, 157 corresponding respectively to positions 102 to 107 in- 45 clusive of drum D.

45 If drum D had been placed in the third position, that is, in position 104 so that segment 118 made contact with contact finger 114, then when motor 150 had moved drum RD to a position such 50 that contact segment 158 contacts contact finger 159 a circuit would be made in which current flows as follows: positive terminal of the source, wires 135 and 136, contact finger 127, contact segment 122, contact finger 125, wire 160, contact 55 segment 111, contact segment 115, wire 117, contact segment 116, wire 161, contact segment 118, contact finger 114, wires 162 and 163, contact finger 159, contact segment 154, wire 164, contact segment 165, wire 166, contact segment 167, contact finger 168, wire 169, coil 170, wire 171 to the negative terminal of the source. Current flowing in the above traced path will energize 60 relay, or selector controlled, or electrically energizable coil 170 moving armature 140 and 171 to the left as viewed in Fig. 6. The movement of armature 140 will break the stick circuit of the relay coil 142 which will cause the armatures 143 and 144 to return to their normal position, that is, the position as shown in Fig. 6, thereby breaking 65 the circuit of the motor 150 so that the motor will stop, thus leaving the sign in the desired third position.

70 The other five positions of the route signs throughout the train will be brought about in an 75

identical manner, the only difference being the positioning of drum D which will be in accordance with the desired face of the sign which is to be displayed.

- 5 Not only does the drum RD of Fig. 6 and the sign connected thereto assume a desired position, but in addition, all other route signs throughout the train assume a like position, as the sign connected with and moving synchronously with drum 10 CRD of Fig. 8 and A'RD of Fig. 10, so that the armature 181 adjacent CRD and the armature 184 adjacent A'RD move to the closed position.

15 It is to be observed that although applicants have shown a route sign only in sections A, C, and 'A', that, if necessary, one or more could be placed in each of the units of the train shown by Fig. 1, it merely being necessary to tap into the control wire and place relays corresponding to 142 and 170 together with a motor corresponding to 150, and a drum corresponding to RD at the particular place where a sign is desired.

- 20 It should be noted that when the route drum RD arrived at the desired position, the armature 171' was moved to the left. This was for the purpose of giving a return indication of the position of the sign. This return indication is to cause a circuit to form in which current flows as follows: positive terminal of the source, wires 135 and wire 173, contact finger 129, contact segment 30 128, contact finger 130, wire 174, 175 and 176, lamp 177, wire 178, armature 171, wires 179 and 180, through couplings 91 and 92 and through couplings 93 and 94, armature 181 in the closed position, wire 182, through couplings 95 and 96, through couplings 97 and 98, wire 183, armature 184 in the closed position, wire 185, lamp 186, wire 187, wire 188, contact finger 189, contact segment 190 of energy drum ED', contact finger 191 and wire 192 to the negative terminal of the 35 source. The circuit just above traced passes through armatures 181 and 184 in the closed position. These are in the closed position because they correspond to and function exactly as does armature 171 as hereinbefore described.

- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

tion by the lamps persist until the energy drum which was moved to the on position is moved to the off position in all cases of normal operation.

If it is desired to exhibit a particular face of the destination type of sign, an operator turns 5 energy drum ED to the on position then moves a drum as D, to a position corresponding to the face to be exhibited, and then pushes destination button 193 to connect wires 194 and 195. When wires 194 and 195 are connected, current flows 10 as follows: positive terminal of the source of potential, wires 135 and 136, contact finger 127, contact segment 122, contact finger 126, wire 194, button 193, wires 195, 196 and 197, armature 198, wire 199, relay coil 200 to the negative terminal 15 of the source of potential. Current flowing in the above traced path moves armatures 201 and 202 to the left hand position, as viewed in Fig. 6, thereby energizing the motor 203 by current in a circuit as follows: positive terminal of 20 the source of potential, wires 204 and 205, armature 202, motor 203 to the negative terminal of the source. Current flowing in the above traced path causes the motor to operate and move the drum DD until it has assumed a position corresponding to the position of drum D, the motor remaining energized even after the button 193 is released by reason of a stick circuit through relay coil 200 identical with the stick circuit through relay coil 142. When the drum DD does arrive 30 at a position corresponding to the drum D, assuming D is in the third position, that is, position 104, then current will flow in a path as follows: positive terminal of the source, wires 135 and 136, contact finger 127, contact segment 122, 35 contact finger 125, wire 160, contact finger 111, contact segment 115, wire 117, contact segment 116, wire 161, contact segment 118, wires 162, 206 and 207, contact finger 208, contact segment 209, wire 210, contact segment 211, wire 212, contact segment 213, contact finger 214, wire 215, relay coil 216, to the negative terminal of the source. Current flowing in the above traced path energizes the relay coil 216 and moves armatures 198 and 217 to the left as viewed in Fig. 6 45 50 thereby breaking the stick circuit for relay 200 and causing armatures 201 and 202 to move to the right as shown in Fig. 6, thereby energizing the motor 203.

Not only does the drum DD of Fig. 6 move together with its sign but also the drum BDD of Fig. 7 together with its sign, and the drum CDD of Fig. 8 together with its sign, and the drum B'DD of Fig. 9 together with its sign, and the drum A'DD of Fig. 10 together with its sign, so 55 that all of the destination signs throughout the train are operated to exhibit the same face.

When the destination signs are operated to show a face armature 217 is moved to the left as viewed in Fig. 6 and also armature 218 of Fig. 7, 60 219 of Fig. 8, 220 of Fig. 9 and 221 of Fig. 10, so that an indication circuit is formed in which current flows as follows: positive terminal of the source of potential, wires 135 and 173, contact finger 129, contact segment 128, contact finger 65 130, wire 174, lamp 222, wire 223, armature 217, wire 224, wire 225, armature 218, wire 226, armature 219, wire 227, armature 220, wire 228, wire 229, armature 221, wire 230, lamp 231, wires 232 and 188, contact finger 189, contact segment 190, 70 contact finger 191 and wire 192 to the negative terminal of the source of potential. Current flowing in the above traced path causes the lamps 222 and 231 to light and so gives an indication that the destination signs throughout the train 75

- 75 It is further to be noted that the return indica-

have moved and have assumed the desired position whereupon the energy drum ED is moved to the off position.

If the trainman desires to operate the third type of signs, that is, the alternative route signs, he proceeds by first moving energy drum ED to the on position then turns the drum D to the desired position, say the third position, that is, to position and then pushes alternative route button 233, so that a circuit is formed in which current flows as follows: positive terminal of the source of potential, wires 135 and 136, contact finger 127, contact segment 122, contact finger 126, wires 137 and 234, button 233, wires 235 and 237, armature 238, wire 239 and relay coil 240 to the negative terminal of the source. Current flowing in the above traced path energizes relay 249 which moves armatures 241 and 242 to the left hand position, as viewed in Fig. 6, thus forming the stick circuit for relay coil 240 through armature 238 and energizing motor 243 by way of armature 242, so that drum SR together with associated signs is moved until the appropriate segment, that is, segment 244, contacts 245, whereupon a circuit is formed in which current flows as follows: positive terminal of the source of potential, wires 135 and 136, contact finger 127, contact segment 122, contact finger 125, wire 160, contact finger 111, contact segment 115, wire 117, contact segment 116, wire 161, contact segment 118, contact finger 114, wires 162 and 246, contact finger 245, contact segment 244, wire 247, contact segment 248, wire 249, contact segment 250, contact finger 251, wire 252 and relay coil 253 to the negative terminal of the source. Current flowing in the above traced path energizes relay coil 253 and moves armatures 238 and 254 to a left hand position, thereby breaking the stick circuit of relay 240.

The drum SR and its associated signs are operated by the flow of current which energizes relay 249, and at the same time relay 255 on Fig. 8, and relay 256 on Fig. 10 are energized so as to cause a movement of drums CSR and A'SR respectively together with their associated signs, so that armatures 257 on Fig. 8, and 258 on Fig. 10 are moved to the left hand position, as viewed in the figures, so that a circuit is formed in which current flows as follows: positive terminal of the source of potential, wires 135 and 173, contact finger 129, contact segment 128, contact finger 130, wires 174, 175 and 176, lamp 259, wire 260, armature 254, wires 261 and 262, armature 257, wires 263 and 264, armature 258, wire 265, lamp 266, wires 267, 232 and 188, contact finger 189, contact segment 190, contact finger 191 and wire 192 to the negative terminal of the source. Current flowing in the above traced paths illuminates the lamps 259 and 266 indicating that the alternative route drums and signs associated therewith have moved to the desired position, whereupon the energy drum ED is moved to the off position.

Instead of using a rotating drum, such as D, for selecting a position corresponding to the desired face of a sign to be exhibited, applicants may use the arrangement as shown in Figs. 11 and 12. Fig. 11 illustrates the possibility of utilizing a central metallic contact with other contacts arranged on the circumference of a circle thereabout for cooperation with a U-shaped metallic member 268 for making connection between the central contact and the circumferential contacts. In Fig. 11 the wire 269 corresponds to wire 160 of Fig. 6, and feeds positive energy to the central contacts 270, 271 and 272 which correspond to

the segment 115 of Fig. 6. If the U-shaped metallic member 268 is connected between one of the central contacts as 270, 271, or 272 and one of the surrounding contacts a circuit is made which corresponds to a circuit made by connection of a metallic segment as 116 on drum D with a contact finger as 113, that is, the surrounding contacts 273, 274, 275, 276, 277 and 278 correspond with the contact fingers 108, 109, 110 and 112, 113 and 114 respectively.

Fig. 13 illustrates the manner in which the drum 77 together with its associated contact segment 78 and contact finger 79 and 80 may be used. This drum and its associated parts may or may not be included within the circuits as shown by Figs. 6 to 10 inclusive. If it is found that a motor such as 150, as shown adjacent RD in Fig. 6, has a tendency to stop before driving pin 71 has completed a movement of a slot such as 72 through an angle of sixty degrees or then turning locking cam 75 into contact with locking wing 76, then the arrangement as shown in Fig. 13 may be used by which the drum 77 and its associated parts are called into action. The drum structure shown in Figure 13 is the drum structure designated RD in Fig. 6 and the wiring connections thereto are just as in Fig. 6 with the exception of the connection between contact segment 167 and relay coil 170. In the construction as shown by Fig. 13 the conductors between segment 167 and relay coil 170 is not continuous, but has its continuity interrupted by drum 77 and associated parts, in that, a wire from segment 167, that is, wire 279 leads from contact segment 167 to a contact finger 79, and another wire 280 leads from relay coil 170 to contact finger 80. The contact 78 is so positioned upon the drum 77 that it connects contact fingers 79 and 80 only after driving pin 71 has moved out of slot 72 of the star wheel 73 after having moved the star wheel 40 through an angle of sixty degrees. As a consequence of this method of operation the circuit for relay coil 170 is not completed through the drum RD until after the drum has been moved precisely sixty degrees or some multiple of sixty degrees, whereupon a segment as 78 closes contact between contact fingers 79 and 80 so that the motor 150 will always move positively and definitely move a sign through exactly sixty degrees at each energization of the motor.

The form of motor circuit shown in Fig. 14 embodies what is commonly known as a "snub" or brake. In Fig. 14, the wire 149 corresponds to the wire 149 of Fig. 6. There is shown, however, a motor having an armature 281 and field coils 282 and 283. After the motor has operated by armature 144 contacting with 166 and then relay coil 142 is de-energized, the armature 144 falls back to its normal position, that is, inclined to the right as viewed in Fig. 14 and in Fig. 6 making contact with wire 284 so that a circuit is completed through armature 144, wire 149, motor armature 281, field coil 282 and wire 284 which is in effect a short circuit upon the motor using one of the field coils in the circuit. This acts as an effectual snub or brake bringing it quickly to a stop instead of allowing it to run freely and coming to a stop gradually. This alternative as shown by Fig. 14 may be used if it is found that with the particular motor used there is too much overrun after the circuit of the motor is broken.

From the foregoing it will be seen that in accordance with the principle of applicants' invention the number of wires extending throughout the train will be one main conductor for each 75

face of the sign having the largest number of faces to be exhibited; one motor relay control wire for each type of sign to be used; and one return indication wire for each type of sign to be used. As applicants have employed signs of three types each having six exhibitable faces, they have consequently shown six main conductors; three motor relay control wires; and three return indication wires, making a total of twelve.

It will be noted that the energy switches ED and ED' are so arranged that one complements the other, that is, if a trainman is operating the signs from the end of the train illustrated by Fig. 6, he would move the energy drum ED to the on position. At this time, the energy drum ED' on the farther end of the train would be in the off position, and necessarily so, in order for the trainman at energy switch ED to receive a return indication of the positioning of the signs, because the return indication wire supplying the lamps with energy is carried to the negative terminal of the source of potential through a segment on the drum ED' which bridges the proper contacts only when that drum is in the off position, and reversely if the signs are operating from the end of the train at which the drum ED' is positioned the drum ED must be in the off position in order to obtain the proper grounding of the return indication wire in order to energize the lamps, such as 186, 231 and 266, at the end of the train at which the drum ED' is positioned.

Although we have particularly described particular physical embodiments of our invention and explained the operation, construction and principle thereof, nevertheless, we desire to have it understood that the forms selected are merely illustrative, but do not exhaust the possible physical embodiments of the idea of means underlying our invention.

What we claim as new and desire to secure by Letters Patent of the United States, is:

1. As an operating means for a changeable sign, the combination of a motor; a shaft; mechanism connected between the motor and the shaft whereby an operation of the motor causes the shaft to revolve; a second shaft mounted to revolve; a sign provided with a movable member movable to a plurality of positions; connections between the sign and the second shaft; a star wheel formed with slots and locking faces on the second shaft; a driver and locking cam on the first shaft cooperating with the star wheel to intermittently move it and lock it between movements; and means for causing the motor to operate; and cooperating means operated by the first shaft and by the second shaft for causing the motor to stop.

2. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia, and each sign movable to bring each indicia to a predetermined position; motors, one operatively connected to each sub-group arranged to move the sign or signs of the sub-group to which it is connected; an indicator individual to each main group a manually positionable selector common to all the main groups, and having a plurality of positions at least equal to the greatest number of distinct indicia on any sign, each position corre-

sponding to a distinct indicia; a motor operated selector associated with each motor; a motor control coil associated with each motor; a selector controlled coil associated with each motor operated selector; a motor control coil manually operable circuit controller individual to each main group; and means including a source of potential and electrical circuits whereby a desired indicia of any sub-group may be positioned, by a manual positioning of the manually positionable selector and the subsequent operation of the manually operable circuit controller individual to the main group to which the sub-group belongs, on a sign on which the desired indicia appears and an indication will be given that the desired indicia has been displayed.

3. In a sign, in combination: a plurality of distinct informational indicia; means movable to a number of positions corresponding to the number of distinct informational indicia whereby any particular one of the indicia is exhibited; a motor for operating said means; connections between the motor and the means including a star wheel formed with slots and locking faces equal, in number, at least to the number of distinct indicia, and a pin and locking cam cooperating with the star wheel and connected to the motor whereby an operation of the motor causes an operation of the said means; manual means including a selector and circuit controller for causing the motor to operate and automatic means controlled by the motor, and including a circuit controller operated by the operation of the motor for causing the motor to stop.

4. In a system of changeable signs, in combination: a plurality of different type signs, each positionable to a plurality of positions, each sign provided with a plurality of faces each provided with informational indicia; a motor associated with one or a group of each type; positionable a selective means determining a corresponding face of each sign to be positioned; means including a manually operable circuit controller for operating the motor to cause the selected face to be positioned; and means for giving an indication that the particular face has been exhibited.

5. In a system of changeable signs, in combination: a plurality of signs, said signs arranged in sub-groups of one or more, the sub-groups arranged in a plurality of main groups, each sign positionable to a plurality of positions and each sign provided with a plurality of faces, each face provided with informational indicia; a motor associated with each sub-group; a selective positionable means determining a corresponding position of each sign to be positioned; a plurality of manually operable means, each associated with a single main group for operating the motors of the sub-groups comprising a main group to cause the selected face of each sign of a sub-group of that main group to be positioned; and means for giving an indication that the particular face has been exhibited.

6. In a changeable sign, in combination: a sign formed with a plurality of faces each bearing informational indicia, and mounted for rotation; a motor operatively connected to the sign to cause it to rotate; a partial circuit for the motor including a source of potential; a first electrically energizable coil; circuit controllers operated by the first electrically energizable coil and being normally in the open position, one of said circuit controllers being included in the motor circuit and completing said motor circuit when closed; a second electrically energizable coil; circuit con-

trollers operated by the second electrically energizable coil, one having a normally closed position and the other a normally open position; means for energizing the first electrically energizable coil including a source of potential and a circuit including the normally closed circuit controller of the second energizable coil; another circuit for energizing said first electrically energizable coil including a source of potential, one of the circuit controllers controlled by the first electrically energizable coil when in circuit closing position due to the energization of the first electrically energizable coil, and a circuit controller of the second electrically energizable coil in normal position, 15 said normally closed circuit controller controlled by the second electrically energizable coil movable from the normally closed position by the energization of the second mentioned energizable coil to break the circuit of the first mentioned energizable coil and so cause the circuit breakers controlled by the first electrically energizable coil to move to normal open circuit position breaking the circuit of the motor thereby causing the same to stop; means for energizing the second electrically energizable coil whereby the normally closed circuit controller controlled thereby is moved to open position and the normally open circuit controller is moved to closed position; an indicator; a partial circuit including a source of potential including the indicator closed by the normally open circuit controller controlled by the second electrically energizable coil whereby the indicator is operated.

7. In a sign system, in combination: a plurality of main groups of signs, each main group consisting of one or more sub-groups, each sub-group of each main group substantially separated from other sub-groups of the same main group and each sub-group consisting of one or 40 more individual signs, substantially adjacent, each sign provided with a plurality of distinct indicia, and each sign movable to bring each indicia to a predetermined position, a separate motor for each sub-group connected to the sign or 45 signs of the sub-group to move the sign or signs to bring the indicia to a predetermined position; a plurality of selective partial circuits, each including a source of potential, the number of circuits being equal in number at least to the number of distinct indicia upon the positionable sign, having the largest number of distinct indicia thereon, and each circuit corresponding with indicia similarly positioned upon each sign and upon being completely closed being determinative of the position assumed by that indicia; a manually operable selective partial circuit closing means located substantially remote from each of the several groups and positionable to partially close any one of the selective partial circuits; a plurality of substantially identical means, one corresponding to each main group; a manually operable circuit closer individual to each means and a source of potential included in each means whereby an operation of any one of said manually operable circuit closers causes all of the motors of all of the sub-groups belonging to the main group to which the manually operable circuit closer operated is individual to operate and position the indicia of the signs of the sub-group connected with the motors with the indicia in a predetermined position; and means for stopping the motor after the indicia has been positioned; and means for giving an indication that the indicia has been positioned.

75 8. In a system of changeable signs, in combi-

nation: a plurality of partial selective circuits each including a source of potential; a manually operable selective circuit closer for partially closing a selected one of the plurality of partial circuits; a motor included in a partial circuit including a source of potential; a first electrically energizable coil; two normally open circuit controllers operated by the electrically energizable coil and each having an open position and a closed position, one of said circuit controllers when in the closed position closing the circuit for the electric motor; a second electrically energizable coil; two circuit controllers operated by the second electrically energizable coil, said circuit controllers having an open and a closed position, one of said circuit controllers being normally in the closed position and the other normally in the open position; a partial energizing electric circuit for the first electrically energizable coil including the normally closed circuit controller of the second electrically energizable coil and the first electrically energizable coil and a source of potential; manually operable means for closing the energizing circuit for the first electrically energizable coil; a second partial circuit for the first energizable coil including a source of potential and one of the normally open circuit controllers controlled by the first mentioned energizable coil and the normally closed circuit controller of the second mentioned energizable coil when that circuit controller is in normal position; a partial indication circuit including a source of potential and an indication device, the normally open circuit controller controlled by the second mentioned electrically energizable coil when closed closing the partial indication circuit whereby the indication device is operated; a selectively positionable multi-circuit sequential circuit controller operable by the electric motor partially closing in sequence each of the selective partial circuits and serving to partially complete a circuit through the second mentioned electrically energizable coil; a final closing circuit controller operated by the motor also included in the circuit of the second mentioned electrically energizable coil and closing that circuit only at a definite point in the rotation of the motor; and a plural faced movable sign operated by the motor to sequentially exhibit the several faces of the sign each of which bears informational indicia whereby any selective partial circuit may be rendered operative by a manual manipulation of the manually operative selective circuit controller, the motor may be operated by the manually operable circuit controller included in the circuit of the first mentioned electrically energizable coil, the selective multi-circuit sequential circuit closer may be operated by the motor to a position corresponding to the position of the manually operable selective partial circuit closer, and the second mentioned electrically energizable coil may be energized to cause the breaking of the circuit of the motor and close the circuit of the indication device giving an indication that the sign has been moved to the position desired, exhibiting the proper face.

9. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia, and means including a selector and a

- manually operable circuit controller whereby any particular distinct indicia of all of the signs of any particular main group may be exhibited.
10. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia, and means including a selector and a manually operable circuit controller whereby any particular distinct indicia of all of the signs of any particular main group may be exhibited and an indication made that the indicia has been exhibited.
11. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia; motors, one associated with each sub-group; and means including a selective manually positionable device and a manually operable circuit controller whereby the motors of all the sub-groups of a particular main group may be caused to operate and cause any particular distinct indicia of all of the signs of the particular main group to be exhibited, and the motor then caused to stop.
12. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia; motors, one associated with each sub-group; and means including a selective manually positionable device and a manually operable circuit controller, whereby the motors of all the sub-groups of a particular main group may be caused to operate and cause any particular distinct indicia of all of the signs of the particular main group to be exhibited, and the motor then caused to stop, and an indication made that the indicia has been exhibited.
13. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia; motors, one associated with each sub-group; and means including a selective manually positionable device, and manually operable devices, one individual to each main group whereby the motors of all the sub-groups of a particular main group may be caused to operate and cause any particular distinct indicia of all of the signs of the particular main group to be exhibited, and the motor then caused to stop.
14. In a sign system, in combination: a plurality of main groups of signs, each main group consisting of one or more sub-groups, each sub-group of each main group substantially separated from other sub-groups of the same main group, each sub-group consisting of one or more substantially adjacent individual signs, and each sign provided with one or a plurality of distinct indicia; motors, one associated with each sub-group; and means including a selective manually positionable device, and manually operable devices, one individual to each main group and indicators, one individual to each main group whereby the motors of all the sub-groups of a particular main group may be caused to operate and cause any particular distinct indicia of all of the signs of a particular main group to be exhibited and the motor then caused to stop and the indicator individual to the particular main group operated to indicate that the particular distinct indicia has been exhibited.
15. In a system of changeable signs in combination: a plurality of different type signs, each sign provided with a plurality of distinct informational indicia; movable means for conditioning the indicia so that it may be exhibited; a motor associated with one or a group of each type; selective positionable means determining the distinct indicia to be exhibited; and means for operating the motor to cause the selected indicia to be exhibited; and means for giving indication that the particular indicia has been exhibited.
